United States Patent Office

Des. 187,857

Patented May 10, 1960

187,857

GOLFING VEHICLE OR THE LIKE

Richard L. Collier, Hollywood, Calif., assignor to Ride Around Manufacturing Company, Los Angeles, Calif., a corporation of California

Application April 13, 1959, Serial No. 55,461

Term of patent 7 years

(Cl. D14—3).

FIG. 1.

FIG. 2.

FIG. 3.

FIG. 4.

Fig. 1 is a side perspective view of a golfing vehicle or the like embodying our new design, viewed from slightly above;

Fig. 2 is perspective view of the other side thereof, viewed from slightly above;

Fig. 3 is rear perspective view thereof, viewed from slightly above and to one side; and

Fig. 4 is a front elevational view thereof.

I claim:

The ornamental design for a golfing vehicle or the like, substantially as shown.
